UNITED STATES PATENT OFFICE.

FRANK HEINZ, OF ATCHISON, KANSAS.

CAR-COUPING.

SPECIFICATION forming part of Letters Patent No. 364,513, dated June 7, 1887.

Application filed April 14, 1887. Serial No. 234,785. (No model.)

To all whom it may concern:

Be it known that I, FRANK HEINZ, a citizen of Bohemia, residing at Atchison, in the county of Atchison and State of Kansas, have invented certain new and useful Improvements in Car-Couplers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in car-couplings; and it has for its object to facilitate the coupling and uncoupling of adjacent cars.

To this end the invention consists in the 20 novel construction and arrangement of the several parts, as will be hereinafter more particularly described, and specifically pointed out in the claims.

In the accompanying drawings, to which 25 reference is had and which fully illustrate my invention, Figure 1 is a perspective view of my device, showing the coupling pin in position when the car is coupled; and Fig. 2 is a longitudinal sectional elevation of the same, showing the pin raised or in the position when the 30 cars are uncoupled.

In the drawings, the letter A indicates a car to the under side and forward end of which is secured one or the inner end of a tilting or inclined frame-work, B, secured pivotally to the inclined side pieces, E E, constituting a part of the frame-work B at its outer or lower end, by means of a rod, b, the inner or free end previously referred to being regulated or adjusted by means of vertical spiral springs b' b² 40 interposed between the under side of the free end of the tilting frame-work B and a cross-piece, C, secured to the side pieces, E E, in the center of which is a perforation, c, through which a pin, D, passes for the purpose of 45 steadyng and holding in place the springs b' b². Secured to the upper part of this cross-piece C, at each end, is a flat bowed spring, (not shown in the drawings,) which, in conjunction with the spiral springs b' b², serves to facilitate 50 the adjustment of the free end of the frame-

work relatively with the draw-head, or any suitable draw-head.

To each inner side of the frame-work B is secured two ways, F F. Within these ways 55 slide two platforms, G G', having rollers g g secured to their under sides, which traverse the bottom of the frame-work to the platform G, traversing the whole distance of the length of the frame-work, while the platform G' traverses but half of its length, an inclined perforation being made in the bottom of the frame-work at the point where the meeting ends of the platforms G G' form a junction. At this point also is made a stop by means of 60 the upper part of the lower part or section of the bottom, by which means the platform G' can descend no farther, but can ascend similarly to the platform G to form a junction at the mouth of the draw-head. Loosely pivoted 65 in the upper end of the frame-work is a roller, H, and adjacent to said roller and secured within an inclined slot, h, is a triangular or nearly triangular piece of metal, I, having a flat steel spring secured to the under side, 70 which serves to give motion or "spring" to the free end of the metallic strip I. J is a coiled spring formed upon the center of a bent rod, j, which has one end secured to the under side 75 of one or the lower end of the platform G' and the other end secured to the rod b, which is in turn secured to the outer or lower end of the side pieces, E E, of the frame-work.

The functions of the roller H, metallic strip I, and coiled spring J serve to operate and 80 elevate the platforms G', upon which the link rests upon the contacting car and assists in passing it into the draw-head, where it is coupled by the coupling-pin, which will be hereinafter referred to.

K is the draw-head, which may be of the ordinary or any preferred construction, provided with the usual mouth or opening and having perforations k k therein for the reception of a coupling-pin, L, having an eye, l, 95 in the top, through which a link is passed and which also passes through an eye formed upon a projecting portion, l', of the angular coupling-rod M. This coupling-rod M is provided with weights upon the ends of its rear projecting arms, N; and also secured at one end thereto is another rod, m, which connects with 100

a weight, m' , at the other end of said rod and top of the car.

The coupling-pin L is surrounded by a coiled spring, N; and secured to the under side of the 5 forward part of the car is one end of another bent spring, O', which lies within the opening formed by the projecting portion of the horizontal angular coupling-rod. Secured to the draw-head, upon its upper surface and in rear 10 of the coiled spring O, is a curved rod, P, which is linked at its free end to the free end of the bent spring O'. Interposed between the rear end of the draw-head bar and a cross-piece, Q, is a spiral spring, R, whereby motion is 15 given to the draw-head bar and relieves the force of the contacting cars.

The coupling and uncoupling of the cars will be obvious when taken in connection with the foregoing description and accompanying 20 drawings.

What I claim as new, and desire to secure by Letters Patent, is—

1. The frame-work B E E, having the platforms G G, rollers g g, ways F F, triangular plate I, and roller H, in combination with 25 springs b' b', cross-piece C, and spring J, arranged and operating as described.

2. The combination, with the frame-work B E E and its attachments, constructed as described, of draw-head K, angular rod M, bent 30 spring O', coiled spring N, coupling-pin L, and curved bar or rod P, all arranged and operating as herein described, and for the purpose set forth.

In testimony whereof I affix my signature in 35 presence of two witnesses.

FRANK HEINZ.
